UNITED STATES PATENT OFFICE.

CHARLES C. STEVENS, OF LOS ANGELES, CALIFORNIA.

AERIAL TORPEDO.

1,331,398.

Specification of Letters Patent. Patented Feb. 17, 1920.

Application filed January 22, 1919. Serial No. 272,471.

To all whom it may concern:

Be it known that I, CHARLES C. STEVENS, a citizen of the United States, residing at Los Angeles, in the county of Los Angeles and State of California, have invented certain new and useful Improvements in Aerial Torpedoes; and I do hereby declare the following to be a full, clear, and exact description of the invention, such as will enable others skilled in the art to which it appertains to make and use the same.

This invention relates to aerial torpedoes, and more particularly to a torpedo or bomb which is specially adapted to be dropped from an aeroplane.

One of the main objects of the invention is to provide an aerial torpedo of very simple construction and operation which may be produced at small cost and is highly efficient.

A further object is to provide a torpedo which is so constructed as to penetrate the target so as to, when exploded, cause great damage thereto.

Another object is to provide a torpedo which may be safely shipped or transported, simple and efficient means being provided for positively locking the firing element of the torpedo against movement, this locking means being readily releasable when it is desired to use the torpedo.

Further objects will appear from the detailed description.

In the drawings:

Figure 1 is a central longitudinal section through a torpedo constructed in accordance with my invention.

Fig. 2 is a side view.

Fig. 3 is a section taken substantially on line 3—3 of Fig. 1.

Fig. 4 is a section taken on line 4—4 of Fig. 1.

Fig. 5 is a section taken on line 5—5 of Fig. 1.

Reference numeral 1 designates a substantially frusto-conical point or nose which is secured in the forward end of the cylindrical body casing 2, which is formed of relatively thin easily frangible steel or other suitable metal. As will be noted, the point 1 is formed of solid steel and is relatively sharp so as to readily pierce a target upon which the torpedo is dropped so as to cause entry of the torpedo into the same. A perforated tube 3 is secured in the base 4 of body 2, this tube projecting into body

casing 2 axially thereof. Tube 3 is adapted to contain an igniting charge 5 of explosive which serves to ignite the main explosive charge 6 contained within body casing 2. A 60 thimble 7 is secured in the rearward or outer end of tube 3, the inner end disk 8 of this thimble being perforated as shown in Fig. 1. The thimble receives a suitable detonating charge 9 of explosive, the outer end of 65 this charge being normally protected by a cover member or cap 10, the thimble, together with this cover member and detonating charge constituting, in effect, a fulminate cap of known construction.

The base portion of body casing 2 is reduced and exteriorly screw threaded to receive a rearwardly tapering casing 11 of relatively thin steel which contains the firing mechanism. Two rods 12 are secured 75 on base 4 of body casing 2 and are disposed diametrically thereof. These rods receive two spaced bars 13 rigidly secured thereto adjacent their ends. These bars support between them a cylindrical key casing 14 in 80 which is rotatably mounted a suitable locking key, this key being provided with a diametric bore 16 through which passes a firing pin 17 slidable in a sleeve 18 carried by casing 14 and mounted coaxial with tube 85 3. The casing 14 is further provided with a relatively short nipple 19 which is in alignment with sleeve 18, this nipple being secured to the inner plate 13 and snugly receiving the inner portion of firing pin 17 90 so as to guide the same. An expansion coil spring 20 is mounted about sleeve 18 and the upper portion of firing pin 17, this spring being confined between the outer bar 13 and a disk weight 21 which is centrally recessed to receive the outer end portion of pin 17 secured therein. This weight is provided with diametrically opposite axially extending bores 22 which receive the rods 12, the weight being slidable longitudinally 100 of these rods. Expansion spring 20 acts to normally hold the weight 21 in raised or outer position, outward movement of this weight being positively limited by an inwardly bowed central stop member 23 carried by casing 11 at the outer end thereof. Normally, key 15 is turned into such position as to be in biting engagement with the firing pin 17, as in Fig. 1, thus effectually locking the firing pin against inward movement so as to prevent accidental discharge 110 of the bomb. When it is desired to use the

bomb, key 15 is turned into such position as to bring the opening 16 thereof into concentric relation with firing pin 17 thus permitting the firing pin to be moved inwardly 5 upon inward movement of weight 21 so as to be brought into engagement with the detonating cap including the thimble 8, explosive charge 9, and hood or protecting member 10 therefor. To permit the key to 10 be turned in the manner stated, casing 11 is provided with a suitable opening 24 positioned in alinement with the key, this opening being normally closed by a slidable door or closure plate 25 which is operative in 15 guide strips 26 positioned at each side of the opening. By inserting a suitable instrument through the opening 24, the stem 15^a of key 15, which is of proper shape, may be readily engaged and the key turned into 20 the desired position. In this manner, the torpedo may be readily rendered inoperative for shipping or transportation purposes, and may be quickly and easily rendered operative by turning the key slightly in the 25 proper direction. Also, all of the parts of the firing mechanism are inclosed in the casing 11 so as to be effectually protected thereby, while the key for rendering this mechanism either operative or inoperative, 30 which is also positioned within the casing, is readily accessible for the purpose stated.

In assembling the torpedo, the head or point 1 is first secured in the body casing 2, after which the main explosive charge 6 may 35 be readily placed in this casing through a suitable filling opening 27 provided through the base 4 for this purpose, this opening being then closed by a disk 28 which is pivoted to the base, as at 29, and is secured in closed 40 position by a turn button catch 30. After the main explosive charge has been placed in the body casing 2, the igniting charge 5 may be placed in tube 3, after which the detonating cap is mounted in the outer end of this 45 tube, the disk weight 22 being then placed upon the rods 12 with firing pin 17 inserted in sleeve 18 and nipple 19, this firing pin extending through the bore 16 of pin 15 in the manner previously described. The casing 50 11 for the firing mechanism may then be secured in position, this casing acting to depress or force inwardly weight 22 into its normal position. After the torpedo has been thus assembled, the key 15 is turned into 55 biting engagement with firing pin 17 so as to render the firing mechanism inoperative.

When it is desired to use the torpedo, key 15 is turned so as to release firing pin 17 60 thus permitting the same to be moved inwardly or downwardly toward the detonating cap in the manner described. When the torpedo is dropped upon a target, the relatively sharp pointed solid steel head 1 65 strikes the target and serves to pierce the

same, the torpedo readily entering into the interior of the target in case it is a structure such as a house, ship, or similar structure. Upon impact of the torpedo with the target, its speed of travel will be abruptly reduced, 70 thus causing inward movement of disk weight 21 due to its inertia against the expansive force of spring 20 so as to bring firing pin 17 into sharp contact with the detonating charge, thus exploding the same 75 and igniting the firing charge 5. The detonating cap, as well as the firing charge, may be either of the instantaneously acting type, or of a slow acting type so as to cause explosion of the main charge of the torpedo 80 shortly after impact of the same with the target and after the torpedo has entered the interior of the target. In this manner, the torpedo is caused to first pass into the interior of the target and then to explode causing 85 much greater damage than would be the case if the torpedo exploded exteriorly of the target and immediately upon impact therewith, as do torpedoes or bombs which are commonly now in use in connection with 90 aeroplane operations. In addition to being provided with the solid steel head 1, and the relatively thin body casing 2, which cooperate to insure piercing of the target by the torpedo and shattering of this body upon 95 explosion of the main explosive charge, this torpedo has its various parts so related as to permit ready and quick assembling of the same thus effecting a material saving in the time, and consequently in the cost, of production. In addition, it is to be noted that the firing mechanism is composed of very few parts, and these parts of very simple and directly acting construction.

It will be evident that there may be slight 105 changes made in the construction and arrangement of the details of my invention without departing from the field and scope of the same, and I intend to include all such variations, as fall within the scope of the 110 appended claims, in this application in which a preferred form only of my invention is disclosed.

What I claim is:

1. In an aerial torpedo, a body casing, a pointed head secured in one end thereof, said casing being adapted to contain a main explosive charge, a detonating charge supported by the base of the body casing centrally thereof for exploding the main explosive charge, spaced guide rods extending from the base of the body casing longitudinally thereof, a weight member slidable on said rods, a firing pin carried by said member and mounted in alinement with said detonating charge for causing detonation thereof upon inward movement of the weight member, means for normally holding said weight member in its outermost position, and means adapted to be moved into engagement 120
2. In an aerial torpedo, a body casing, a pointed head secured in one end thereof, said casing being adapted to contain a main explosive charge, a detonating charge supported by the base of the body casing centrally thereof for exploding the main explosive charge, spaced guide rods extending from the base of the body casing longitudinally thereof, a weight member slidable on said rods, a firing pin carried by said member and mounted in alinement with said detonating charge for causing detonation thereof upon inward movement of the weight member, means for normally holding said weight member in its outermost position, and means adapted to be moved into engagement 125
3. In an aerial torpedo, a body casing, a pointed head secured in one end thereof, said casing being adapted to contain a main explosive charge, a detonating charge supported by the base of the body casing centrally thereof for exploding the main explosive charge, spaced guide rods extending from the base of the body casing longitudinally thereof, a weight member slidable on said rods, a firing pin carried by said member and mounted in alinement with said detonating charge for causing detonation thereof upon inward movement of the weight member, means for normally holding said weight member in its outermost position, and means adapted to be moved into engagement 130

with said firing pin for securing the same against movement in either direction.

2. In an aerial bomb, a body casing adapted to contain a main explosive charge, a detonating cap secured in the central portion of the base of said casing, a rearwardly extending casing secured to the base portion of said body casing, a weight member supported therein for movement toward and away from the body casing, means for normally forcing the weight member away from said body casing, means carried by the second mentioned casing for positively limiting outward movement of the weight member, a firing pin mounted in axial alinement with said cap carried by the weight member, and means for securing the firing pin against movement toward the cap.

3. In an aerial bomb, a body adapted to contain an explosive charge, a detonating cap supported by said body centrally of the base thereof, guide rods extending rearwardly of the body and secured to the base of the same, a weight member slidable upon said rods, an inwardly directed pin secured in said weight member centrally thereof, a substantially cylindrical key rigidly supported by the rods midway between the same, a key mounted in said casing and provided with a diametric bore, said pin extending through the casing and through the bore of said key, the key being adapted to be turned into biting engagement with the pin to lock the same against movement, and means for normally holding the weight member in its outermost position so as to prevent contact of said pin with the detonating cap.

4. In an aerial torpedo, a body adapted to contain a main explosive charge, a detonating cap secured in the base of said body centrally thereof, guide rods secured to the base of the body diametrically of the same and extending rearwardly therefrom, a weight member slidable on said rods, an inwardly directed firing pin secured in said weight member centrally thereof, a supporting bar rigidly secured to said rods adjacent the inner ends thereof, a casing carried thereby midway between the rods, said casing slidably receiving the inner end portion of the firing pin, a key mounted in the casing and provided with a diametric bore receiving the pin, said key being turnable into biting engagement with the pin so as to prevent movement thereof, an expansion coil spring mounted about the pin and confined between said bar and the weight member so as to normally hold the weight member in its outer position, and a casing secured upon the base portion of said body and inclosing said rod and weight member and associated parts, said casing being provided with a member engaging the weight member so as to positively limit outward movement thereof, the casing being further provided with an opening positioned to permit ready access to the key for turning the same into or out of operative position.

In testimony whereof I affix my signature 70
in presence of two witnesses.

CHARLES C. STEVENS.
